[57] CLAIM

The ornamental design for a hand-tool for applying grommets and the like, substantially as shown.

DESCRIPTION

FIG. 1 is a perspective view of a hand-tool for applying grommets and the like showing my design;

FIG. 2 is a top plan view thereof;

FIG. 3 is a front elevational view thereof;

FIG. 4 is a side elevational view thereof;

FIG. 5 is a rear elevational view thereof; and

FIG. 6 is a bottom plan view thereof.
